MEANS FOR MINING STREAMS

Ellis Mallory, Altadena, Calif.

Application May 25, 1932, Serial No. 613,467

3 Claims. (Cl. 61—2)

My invention relates to a simple method for diverting the flow of a live stream from a portion of its bed so that certain operations can be carried on in the portion of the bed thus dried.

5 The invention further relates to a method of mining stream beds to recover placer gold or other valuable minerals or materials therefrom.

Valuable metals, such as gold, are found in many streams, and much of such valuable deposits is recovered from stream beds. Where the 10 conditions are such that a dredge may be floated on the stream, mining operations are carried on. In some instances the materials forming the bed of a stream are removed by use of hydraulic dredging equipment; but many streams are encountered in which recovery or mining of materials is not practical in the above described manners. For instance, the stream may be narrow and swift at the point at which it is desired 15 to conduct the mining operations; the point at which the operations are to be conducted may be relatively inaccessible to heavy machinery; and the stream may be situated between relatively steep canyon walls. In addition to the foregoing, it is often found that the stream bed is so 20 rocky that removal thereof cannot be accomplished by dredges; accordingly, the deposits of gold or other valuable metals under and between the rocky formation of the stream bed remain 25 inaccessible.

My present invention is of considerable importance in that it provides a simple method and means for mining the bed of a stream heretofore considered impractical or inaccessible.

30 My invention comprehends a simple method and means whereby a portion of a stream bed may be made dry by the diversion of the stream flow therefrom, thereby making it possible to mine the bed of a stream and remove therefrom 35 all of the valuable constituents.

In its simplest form the practice of my invention embraces the placing of flexible conduit members, such as tubes of canvas, cloth, or rubberized fabric, with the upper or mouth ends 40 thereof in the stream bed in position to receive a maximum portion of the water constituting the flow of the stream. The front or mouth ends of the conduit members are placed in the stream bed at a point above the part in which it is desired 45 to conduct the mining operations, and the following or intermediate portions of the conduit members are placed or located in positions disclosing the stream bed to mining operations. The water of the stream, or a greater portion 50 thereof, is in this manner caused to circumvent

the zone of the stream bed in which the mining operations are to be conducted. If the stream is flowing through a walled canyon, the flexible conduit members carrying the flow of the stream may be supported one above the other on the 5 canyon walls by means which my invention provides, or in such instances it may be desirable to lay or stack one flexible conduit member on the other along one side of the stream bed, thereby disclosing a part of the stream bed to 10 the mining operations. The particular manner in which the invention is employed varies in accordance with the character of the stream to be mined, namely, whether it is sluggish or swift, small or large. If the stream is accessible and 15 is of such size that a barge may be anchored thereon, the forward or mouth ends of the conduit members may be secured to the barge, and a float then secured to the rearward or discharge end of each conduit member to float it down the 20 stream. Where the stream is small, the operation of placing the flexible conduit members may be conducted from one side of the stream or from a platform suspended by cables.

The essential elements for the practice of the 25 invention include one or more flexible conduits in accordance with the amount of water to be handled, and simple means for securing the forward or mouth ends of the conduits in positions to receive water from the flow of the stream. 30 For this purpose I find that a metal ring, or ring of other rigid heavy material such as concrete, may be attached to the forward end of each conduit to hold it open to the entry of water and also to serve as a weight to hold it 35 against the stream bed. In conjunction with this anchorage means I provide means for holding the mouths or entrance members in positions facing or confronting the stream flow, such means also resisting all downstream movement 40 of the conduit members and the parts associated therewith. Where shore operations are required in the installation of the equipment for diverting the stream flow, a cable may be stretched across the stream at a point above the portion 45 to be mined, and the respective conduit members, wound on spools or drums, may be carried to their desired positions above the stream on a traveler. As the float member secured to the discharge end of each conduit member carries 50 the conduit member down the stream, such conduit member will be unwound to its full length. After such unwinding operation the conduit members may be secured by extending cables 55 from an anchorage means to the inlet members,

thereby holding the mouths of the conduit members in the desired positions to receive the flow of the stream.

Further objects and advantages of the invention will be made evident from the following part of the specification.

Referring to the drawing, which is for illustrative purposes only,

Fig. 1 is a perspective view showing a simple embodiment and practice of the invention in the bed of a relatively small stream.

Fig. 2 is an enlarged cross section on a plane represented by the line 2—2 of Fig. 1.

Fig. 3 is an enlarged cross section on a plane represented by the line 3—3 of Fig. 1.

Fig. 4 is an enlarged longitudinal vertical section showing the mouth end of a flexible conduit member and a simple form of inlet and anchorage means therefor.

Fig. 5 is a partly sectioned view showing a conduit member mounted on a reel or spool.

In Fig. 1 I show a stream bed 11 situated in a cut between relatively steep walls 12 and 13. As shown in Figs. 2 and 3, the stream bed 11 may include a layer 14 of rock, sand, and silt containing the valuable mineral deposits, such as gold, to be reclaimed. Assuming that the portion 15 of the stream bed 11 is to be mined, a plurality of flexible conduit members 16 wound 30 on reels or spools 17 are transported to a position 18 above the portion 15 in which the mining operations are to be conducted. Floats of any desired kind are secured to the discharge ends of the conduit members 16, and these conduit members are floated downstream and are unwound from the spools 17. As shown in Fig. 4, each conduit member consists of a tube 20 of flexible, waterproof material, such as canvas or cloth which has been rubberized or otherwise suitably waterproofed. The lengths of the conduits 16 may vary from a hundred to a thousand feet, as conditions may require, and the circumferential dimensions of the conduits may vary from inches to feet in accordance with the quantity of water flowing in the stream bed. In the forward or mouth end 21 of each conduit member 16 a tubular or cylindrical inlet member 22 is placed, and the conduit member 16 is secured thereto by encircling clamps 23 which coincide with circular grooves 24 in the body of the inlet member 22. At the forward end of each inlet member 22 eyelets 25 or other cable-securing means are mounted. For ordinary purposes, three of such cable-securing means substantially equally spaced are sufficient. From the eyelets 25 cable means 26 are carried forwardly or upstream to a suitable stationary supporting structure, such as a cable 27 stretched across the stream between posts 28. The opening 30 of each inlet member 22 may be guarded by a screen or grillage 31.

The weight of the inlet members 22 causes their submergence in the water of the stream and causes them to lie on the stream bed so that water 32 flowing downstream will enter the openings 30 of the inlet members 22 which are held in positions confronting the flow of the stream by the three-point engagement of the cable means 26. This water flows through the length 70 of the conduit members 16 and may be again discharged into the stream bed, as indicated at 29, or elsewhere, as desired.

As shown in Fig. 1, the cable means 26 are varied in length so as to offset the inlet members 22 in such a manner that the flow of the

stream which passes one inlet member will be received by a succeeding inlet member. By a suitable placement of the inlet members and the provision of sufficient conduit capacity, the entire flow of the stream, or the greater portion 5 thereof, may be caused to circumvent the portion 15 of the stream bed. In Fig. 2 which is a section taken adjacent the forward ends of the conduit members 16, they are shown filled with water 34 constituting the flow of the stream 10 and in side-by-side relation between the side walls 12 and 13. Fig. 3 is a section through the portion 15 of the stream bed which is to be mined, and in order to disclose an area 35 of the stream bed, the intermediate portions of the conduit members 16 are placed along the right side of the stream bed in stacked relation by placing such intermediate portions of the conduit members 16 one upon the other in the manner shown.

The invention also provides means for supporting or holding the conduit members 16 in desired positions to disclose a portion of the stream bed 11. In this disclosure such means consists of tabs 36, secured to the fabric walls 25 of the conduit members at suitable intervals, and cables 37, whereby one or more of the conduit members 16 may be held against a side wall, such as the wall 13, the upper ends of the cables 37 being tied to stationary posts 38. 30

The disclosed area 35 constituting at least half of the stream bed 11 through the portion 15 thereof may be mined by removing the uncovered portion of the layer 14 down to the rock bottom 41 of the stream bed 11. The large and 35 small rocks and stones 42 may be removed to give access to the metal-bearing sand wedged therebetween, thereby making it possible to remove the most valuable portions of the deposits in the stream bed, for the gold or other metal, 40 being relatively heavy, tends to settle to the bottom. After one side of the portion 15 of the stream bed 11 has been mined in the foregoing manner, the intermediate portions of the conduit members 16 may be moved over to the left 45 side of the stream bed, or the rightward portion of the layer 14 lying under the conduit members 16 may be removed from the left side of the stream bed.

My invention is of great value due to its inherent economy resulting from simplicity of the apparatus employed, the simple manner in which it may be installed and secured, and its removability after the mining operations in a particular part of the stream bed have been 55 completed. The conduit members may be removed from the stream bed and rolled up so as to be transported to another location without loss. Where wood flumes are built to divert the flow of a stream, such wood flumes cannot be 60 ordinarily reclaimed and are often destroyed by freshets, thereby occasioning a loss. My apparatus may be removed from and replaced in a stream bed in a relatively short time and at a relatively small cost as conditions may require. 65 Accordingly, where there is an impending freshet or flood, the conduit members 16 may be quickly removed and may be later re-installed so that the mining operations may be continued, or the freshet water may be allowed to pass 70 through, over, and around the conduit members without damage.

Although I have herein shown and described my invention in simple and practical form, it is recognized that certain parts or elements 75

thereof are representative of other parts, elements, or mechanisms which may be used in substantially the same manner to accomplish substantially the same results; therefore, it is 5 to be understood that the invention is not to be limited to the details disclosed herein but is to be accorded the full scope of the following claims.

I claim as my invention:

- 10 1. Equipment of the character described, for removing a flow of water from a stream bed, comprising: a conduit member consisting of a tubular wall of flexible material, the forward end of said conduit member being adapted to receive a flow of water from said stream; an inlet member connected to the forward end of said conduit member, said inlet member being adapted to hold the mouth of said conduit member open and to sink the same to the stream bed; a cable spanning said stream bed forwardly of said conduit member; and lines connecting between said inlet member and said cable to hold said conduit member in position.

2. Equipment of the character described, for removing a flow of water from a stream bed, comprising: a plurality of conduit members, each of said members consisting of a tubular wall of flexible material, the forward ends of said conduit members being adapted to receive a flow of water from said stream; an annular inlet member secured in the inlet opening of each of said conduit members and adapted to hold said inlet openings open and to sink said conduit members to the stream bed; a stationary anchoring cable spanning said stream above said conduit members; and cables connecting between said inlet members and said stationary anchoring cable for holding said conduit members in position facing the flow of water in said stream. 5 10 15

3. A combination as set forth in claim 2, including cables secured to said conduit members at points intermediate the ends thereof for holding said conduit members in superimposed relationship against a wall of said stream bed. 20
